UNITED STATES PATENT OFFICE.

WILLIAM KAUT, OF UNIVERSITY CITY, MISSOURI.

TOE-MOLDING MACHINE.

Application filed January 30, 1928. Serial No. 250,668.

This invention relates generally to machines for making apparel shoes, and more specifically to an improved toe-molding machine, the predominant object of the invention being to produce a machine provided with means for molding the toe of an apparel shoe and for turning the lasting allowance of the box toe, lining and upper, or of the box toe and upper only, outwardly flush with the bottom of the last, to provide the shoe with a marginal flange portion to which the sole of the shoe may be attached.

In following out my invention, and in the use of my improved machine, I apply heat to the portion of the material of which the box toe is to be formed which constitutes the lasting allowance of the box toe, and in this manner cause the tar-like substance with which the box toe material is treated to become sticky, or tacky, enough to stick or weld together the box toe material, lining and upper. At the same time the lasting allowance of the box toe, lining and upper are shaped by the heat-applying means so as to provide the shoe with an outwardly extended marginal flange, which is thereafter permitted to cool and to become permanently set, whereby it permanently retains the shape given to it by the heated shaping means.

With the foregoing and other objects in view, the invention comprises the novel construction, combination and arrangement of parts hereinafter more specifically described and illustrated in the accompanying drawings, wherein is shown the preferred embodiment of the invention. However, it is to be understood that the invention comprehends changes, variations and modifications which comes within the scope of the claims hereunto appended.

Fig. 1 is a front elevation of a machine made in accordance with my invention.

Fig. 2 is a side elevation of the machine illustrated in Fig. 1.

Fig. 3 is a fragmentary section showing the molding plate carrier and parts associated therewith.

Fig. 4 is a front elevation of the mechanism shown in Fig. 3.

Fig. 5 is a perspective of the molding plate.

Fig. 6 is an enlarged vertical section of the means for supporting the toe portion of the shoe being operated upon by the machine.

Fig. 7 is a section taken approximately on line 7—7 of Fig. 6.

Fig. 8 is a fragmentary detail showing the last-holding pin of the machine. 60

Fig. 9 is an enlarged view, partly in plan and partly in horizontal section, taken on line 9—9 of Fig. 2.

Fig. 10 is an enlarged cross section on line 10—10 of Fig. 2. 65

Fig. 11 is a vertical section on a reduced scale, showing the mechanism illustrated in Fig. 9.

The particular machine illustrated in the drawings is a multiple one, that is to say, 70 said machine comprises four distinct sections A, B, C and D (Fig. 1), each of which is a duplicate of the other sections, and each section is a machine in itself, with the exception that only one means for heating and 75 shaping the marginal flanges at the toe portions of the shoes is associated with a pair of sections. In view of the fact that with the exception noted each section is complete unto itself and is a duplicate of the 80 other sections, only one section will be described herein, and the same reference characters will be employed to designate like parts in the various sections.

Referring now to the drawings, 1 designates the standard, or base, for the operating parts of the machine, to which is attached at its forward face and adjacent to its upper end a casting 2. The casting 2 comprises a pair of side members 2', and 90 is provided with a plurality of cross members 3 connecting said side members to the lower one of which a lug 4 is integrally formed. Each of the side members 2' is recessed longitudinally at its inner and forward edge, as shown in Fig. 9, and 5 designates side plates which are secured longitudinally of said side members in a manner to overlap the recesses and provide vertically disposed guideways 6. The lug 4 is provided 95 with a vertically disposed threaded opening formed therethrough, which is for a purpose to be hereinafter set forth.

7 designates a member which is provided with a pair of laterally extended fins, or 105 guides, 8 (Fig. 9). The fins or guides 8 are extended into the guideways 6 already referred to, and are capable of moving longitudinally thereof, said guides 8 being of substantial height, as shown in Fig. 11. The 110 member 7 extends from a point slightly to the rear of the guides 8 to a point some dis-

tance in advance of said guides (Fig. 11), and at its forward end said member is provided with an upturned lug 9. As shown clearly in Figs. 10 and 11, the member 7 is provided with a channel 10 which extends from the inner face of the lug 9 to the rear end of said member. Also, the member 7 is provided with a dove-tail guide 11, which extends longitudinally thereof substantially from end to end of said member. Mounted on the member 7 is a member 12 (Fig. 10) provided with a dove-tail groove 13 which receives the dove-tail guide on the member 7, said dove-tail groove being extended longitudinally of the member 12. The member 12 is provided with a lug 14 which extends downwardly from said member into the channel 10 formed in the member 7, said lug 14 being provided with a threaded opening formed therethrough, as shown in Fig. 11. 15 designates a threaded rod or screw, which passes through the threaded opening formed through the lug 14, so that the threads on said rod engage the threads within said opening. The rod 15 has a reduced portion which extends through an aperture in the upturned lug 9 at the forward end of the member 7. The rod 15 has a hand-wheel 16 fixed to it at its outer end, and the hub portion of the hand-wheel and the shoulder at the point where the reduced portion of said rod joins the main threaded portion thereof contact with the opposite faces of the lug 9, so that the rod may rotate axially without moving longitudinally of the lug 9. It is obvious that rotation of the rod 15 by manipulation of the hand-wheel 16 will result in the member 12 being moved longitudinally of the member 7 in one or the other direction, depending on the direction of rotation of the rod.

Extended upwardly from the member 12 at the opposite edges thereof is a pair of lugs 17 (Figs. 9 and 10), and mounted between said lugs is a block 18, there being a pivot pin 19 extended through openings in said lugs and through an opening formed through said block at one end thereof, whereby said block is pivotally secured to said lugs. At the end of the block 18, opposite to the end thereof through which the pivot pin passes, said block is provided with a flange 20 having a vertically disposed threaded aperture through which a screw 21 extends. The lower end of the screw 21 bears against the top face of the member 12, as shown in Fig. 11, and it is obvious, in view of this arrangement, that by rotating the screw axially the outer end of the block may be adjusted upwardly and downwardly, depending on the direction of rotation of the screw.

The block 18 is provided with a non-circular aperture into which the lower end of a last pin supporting member 22 extends

(Fig. 11), said member 22 having a vertically disposed arm 23 pivoted to it at the point indicated by the reference character 24, and the last pin 25 being extended upwardly from said arm. The last pin supporting member 22 is bifurcated, as shown in Fig. 11, one leg thereof being shorter than the other, and a portion of the vertical arm 23 is extended between the legs of said bifurcated portion of said member. Also, the portion of the vertical arm which is extended between the legs of the bifurcated portion of the member 22 is provided with an arcuate slot 26 (Fig. 8), and a suitable pin 27, which may or may not be threaded, as desired, is passed through the shorter of the legs of the bifurcated portion of the member 22 and into the arcuate slot 26. In view of this arrangement, it is plain that the vertical arm 23 may move about the pivot 24, and it is likewise plain that movement of said arm 23 will be limited by the slot 26 and the pin 27.

By referring particularly to Figs. 7, 9, 10 and 11, it will be noted that the member 12 is provided at its upper face with a dove-tail guide 28, which extends from a point removed inwardly a slight distance from the lugs 17 (Fig. 9) to the inner end of said member. It will also be noted by referring to the view mentioned that the dove-tail guide 28 is provided with a channel, which extends longitudinally from end to end thereof, in which is located a toothed bar 29 which is of approximately the same length as the dove-tail 28, and extends above the top face thereof slightly. 30 designates a hollow member, preferably of cylindrical form, which is provided at opposite sides of the opening formed therethrough with dove-tail recesses, the oppositely disposed dove-tail recesses referred to providing a dove-tail groove through the member 30 into which the dove-tail guide 28 on the member 12 extends, which, in the absence of something preventing it, would permit the member 30 to be moved longitudinally of the dove-tail guide 28 without becoming displaced vertically therefrom.

31 designates a member which is of approximately the same diameter as the opening within the member 30, and as shown in Figs. 6 and 7, said member 31 is arranged within the opening in the member 30. The member 31 is provided with a vertically disposed elongated slot 32 (Fig. 6), into which the inner end portion of a screw, or other suitable pin 33, extends, said screw 33 being extended through an aperture formed in the upper portion of the member 30. The member 31 is provided with a tooth 34, which is adapted to be introduced between pairs of adjacent teeth formed on the bar 29, and in view of the connection between the members 30 and 31 produced by the slot 32 and pin 33.

33, it is plain that the member 31 may be moved upwardly with respect to the member 30, and in this manner move the tooth 34 above the toothed bar 29, so that the members 30 and 31 may be moved longitudinally of the dove-tail guide 28.

Supported by the member 31 at the top thereof is a rotatable element 35, which includes an enlarged head 36 having a knurled 10 edge and a downwardly extended portion 37 of reduced diameter. The reduced portion 37 of the element 35 is circular in cross-section and fits closely into the upper end of a vertical opening 31' formed in the member 15 31, and said portion 37 is provided with a continuous circumferential groove 38 into which a screw or other pin 39, which extends through a portion of the member 31, projects (Fig. 6). In view of this arrangement, 20 the element 35 may be rotated with respect to the member 31, the groove 38 during such rotation moving relatively to the screw 39, but because the lower portion of the wall of the groove overlaps the screw 39, said element 25 35 may not be moved upwardly with respect to said member 31. The rotatable element 35 is provided with a threaded, vertical opening 40 formed therethrough and extended through said opening is a vertically disposed screw 41, having a slightly reduced upper end. The reduced upper end of the screw 41 is extended into a socket formed in the lower end of a toe cushion support 42, there being a pin 43 employed 30 for securing the screw and toe cushion support together. The toe cushion support is hollow and open at the top, and said support is semi-circular in front elevation, as shown in Fig. 7, and the hollow interior thereof receives 35 a toe pad 44 formed of rubber, or leather, or other suitable material.

When the element 35 is rotated with respect to the member 31, as already described, it is plain that the coating threads on the screw 41 and within the opening 40 will cause the screw together with the toe cushion support and the toe cushion, to be moved upwardly or downwardly, depending on the direction of rotation of the element 35.

Referring now to Figs. 1, 2 and 11, 45 designates a vertically disposed screw which is extended through the threaded vertical opening formed through the lug 4 in a manner to cause the threads on said screw to cooperatively engage the threads on the screw. The screw 45 has a hand-wheel 46 fixed to it at its lower end to facilitate axial rotation thereof, and at its upper end said screw is provided with a reduced, circular portion 47, which extends into an aperture formed in the member 7 at the lower portion thereof. The upper face of the reduced, circular portion 47 and the shoulder formed at the point where the reduced portion joins the

main body of the screw contact with portions of the member 7, consequently, when the screw 45 is rotated axially by manipulation of the hand-wheel 46 to cause said screw to be moved longitudinally of its major axis, vertical movement will be imparted to the member 7, whereby all of the parts already described which are associated with said member 7 will be adjusted vertically.

Mounted at the upper end of the base 1 of the machine is a member 48 (Figs. 1 and 2), which includes a pair of spaced apart upright wall portions 49 (Figs. 1, 3 and 4), each of which is provided with a guideway 50. 51 designates a carrier, which is provided with outwardly extended flanges 52 which extend into the guideways 50, whereby said carrier may be moved with relation to said wall portions in a direction parallel with the guideways 50. By referring to Figs. 3 and 4 of the drawings, the more or less irregular shape of the carrier will be apparent. In these views the body portion 51' is shown as being extended transversely of the space between the pair of wall 90 portions 49, with the opposite side edges thereof terminating just short of said wall portions (Fig. 4). Projected forwardly from the front edge of the body portion 51', and extended outwardly in a transverse direction from the opposite side edges thereof, is a pair of bars 53 on which the guides 52 are formed, said bars preferably being formed integrally with said body portion 51'. In like manner, the bars 53 extend a 100 slight distance upwardly above the top of the body portion 51', and said bars are provided with notches 54 which extend longitudinally thereof.

Formed in the top face of the body portion 51' of the carrier 51 is a channel 55, which extends from the front edge of said body portion to a point slightly in advance of the rear edge thereof, and mounted immediately above said channel is a flat spring, 110 or other resilient member 56. The flat spring is secured to the body portion 51' at the rear thereof, as shown in Fig. 3, and at its forward end said flat spring is provided with an upstanding projection 57, which has 115 an inclined face. 58 designates the toe-molding plate of my improved machine, said plate being more or less U-shaped as shown in Fig. 5, and being of such width and thickness that its opposite edge portions may be 120 introduced into the notches 54 in the bars 53 at the forward ends of said notches and slid longitudinally of said notches. The plate 58 is provided with an aperture 59 adjacent to its rear edge and at its approximate transverse center, and when the plate is slid longitudinally of the notches 54 as described, the rear edge of said plate will contact with the inclined face of the projection 57, whereby the flat spring on which 130

said projection is arranged will be cammed downwardly in a manner to cause the plate to pass over said projection until the aperture 59 moves into vertical registration therewith, when said incline faced projection will snap into said aperture 59. When the incline faced projection is located within the aperture 59 as described, the straight face thereof will be in contact with the rear 10 wall of said aperture, and the forward faces of projections 57' formed on the body portion 51' will contact with the rear edge of the plate 58. In this manner the plate 58 will be attached to the carrier 51 and 15 will move with it when motion is imparted thereto.

60 designates a cross member which is secured to the body portion 51' of the carrier 51 at the rear thereof (Fig. 3), and 61 designates a pair of downwardly extended lugs which preferably are formed integrally with the body portion 51', at the forward edge thereof. 62 designates a member, the opposite edge portions of which are extended 25 into oppositely disposed guideways 63 (Fig. 4) at the lower portion of the body portion 51', which guideways extend from front to rear of said body portion. The member 62 is in contact with the lower face of the body 30 portion 51' of the carrier 51, and is interposed between the cross member 60 and the downwardly extended lugs 61, and said member is in turn provided with downwardly extended lugs 64 which are in alignment with the lugs 61. The lugs 61 and 35 64 are provided with spring seats, and interposed between each cooperating pair of lugs and seated in the spring seats thereof is a coil spring 65; and as a result of the 40 expansion of said coil springs, the member 62 is forced rearwardly until the rear edge thereof contacts with the forward edge of the cross member 60 (Fig. 3).

66 designates a bar which is carried by 45 the carrier and extends transversely with respect thereto, and 67 designates upstanding lugs which are arranged adjacent to the opposite ends of said member. Pivotally supported by the lugs 67 is a weight 50 68, said weight being in the form of a U-shaped bar, and being capable of being moved about its pivots 69 from the position in which it is shown in Fig. 3 by full lines to the position suggested in said view by 55 dotted lines. The weight 68 is provided with a handle 70 to facilitate handling thereof.

71 designates a toggle comprising a pair of arms pivotally connected together at their 60 inner ends, the outer end of the rearmost of said arms being pivotally attached to a stationary part of the machine at 72 (Fig. 2), and the outer end of the forward arm being pivotally attached at 73 to a lug 74 65 extended downwardly from the member 62.

The inner ends of the arms, which are pivotally attached together, have pivotally secured to them at the point of attachment a rod 75, which extends downwardly to a point adjacent to the lower end of the base 70 1 of the machine, at which point the lower end of the rod 75 is pivotally attached to the inner end of a foot pedal 76, which foot pedal is in turn pivoted at 77 to a member 78 fixed to the base of the machine. 79 75 designates a coil spring, one end of which is attached to the toggle 71 at the point where the two arms comprising the same are attached together, and the other end of said spring is attached to a stationary part 80 of the machine, so that the inner attached ends of said arms will be drawn downwardly.

It is obvious that in the operation of the machine pressure on the outer end of the 85 foot pedal 76 will move the inner ends of the arms comprising the toggle 71 upwardly, and as the rearmost arm of said toggle is fixed to the machine frame, the forward arm of the toggle will be moved forwardly of 90 the machine, carrying the carrier 51 with it, which carrier will slide longitudinally of the guideways 50. The downward movement of the foot pedal 76 will be continued until the pivotally attached inner ends of 95 the arms comprising the toggle 71 pass dead center, or in other words, to a position where they are inclined upwardly toward their inner ends, where upward movement of said pivotally attached inner ends will stop. 100 When the toggle is in the position described, it will be maintained in a locked condition, and the carrier will be maintained in a forward or advanced position.

80 designates a toggle trip lever which is 105 pivoted at 81 to suitable brackets fixed to the machine, said trip lever being arranged in vertical alignment with the toggle 71 and having a portion 82, which contacts with inner portions of the arms comprising 110 the toggle when said trip lever is swung on its pivot, in a manner to force said pivotally attached inner ends of said arms downwardly to break the toggle and permit the spring 79 to return it to the position in which 115 it is shown in Fig. 2. The trip lever 80 is provided with a handle portion 83 and a weighted portion 84 to return it to the position in which it is shown in Fig. 2 after said lever has been operated.

Pivotally attached to the base of the machine at the point indicated by the reference character 85 is a second foot pedal 86, to which a vertically extended rod 87 is pivotally attached at the point indicated by the 125 reference character 88. The upper end of the rod 87 is pivotally attached at 89 to a member 90, which member is provided with a tubular portion 91. 92 designates a vertically disposed rod which is arranged for 130

vertical movement in suitable bearings 93, and said rod 92 extends through the tubular portion 91 of the member 90 and is rigidly fixed thereto by a set screw 94. Fixed to 5 the rod 92, adjacent to the upper end thereof, is a collar 95, and mounted on said rod above said collar is a member 96 having a vertically disposed tubular portion 96^a and a horizontally disposed tubular portion 96^b. 10 The vertically disposed tubular portion 96^a surrounds the upper portion of the rod 92, the lower face thereof resting on the collar 95, and suitable means, such as the nut 96' and washer 97, is employed to prevent upward 15 displacement of the member 96 with respect to the upper end portion of the rod 92. The member 96 is capable of swinging in an arc of a circle about the rod 92.

Extended into the tubular portion 96^b is 20 a horizontally disposed rod 98, said tubular portion being provided with an elongated slot 99 through which a screw or similar element 100 is passed, which screw is rigidly associated at its inner end with the rod 98. 25 Fixed to the rod 98 at the forward end thereof is a handle 101, and pivotally attached to the lower end of said handle at the point designated by the reference character 102 is a heating and pressing iron 103. 30 The heating and pressing iron 103 is provided with a flat lower pressing face, and said iron is provided with an opening formed therein into which a suitable electrical heating unit 104 is extended (Fig. 2), 35 the handle 101 being hollow, and the electrical conductors 105 being passed through the handle to the bottom portion thereof, where they emerge from said handle and pass to the extended portion of the electrical 40 heating element where same is attached to the heating and pressing iron. 106 designates a coil spring, one end of which is attached to the upper end of the rod 87 and the other end thereof being secured to a stationary 45 part of the machine. The function of the spring 106 is to return the heating and pressing iron 103, and its associated parts, to their elevated positions after they have been drawn downwardly by depression 50 of the forward end of the lever 86.

In the operation of my improved machine, a last L, shown in dotted lines in Fig. 2, is mounted on the last pin 25 in the usual manner. The last L will, of course, have the 55 upper, lining and box toe material of a shoe mounted on it, and the lasting allowance, or the portions of said shoe elements which are subsequently shaped to provide an outwardly extended flange on the shoe, are extended upwardly. Assuming that the shoe 60 is the first of a size to be operated upon by the machine, the first operation will be to properly position the toe cushion 44 with respect to the toe portion of the shoe. This 65 is done by moving the member 31 upwardly until the tooth 34 at the lower end thereof clears the teeth on the bar 29, after which the entire assembly, including the members 30 and 31, may be slid longitudinally of the dove-tail guide 28. When the toe cushion 70 has been positioned in its proper position with respect to the longitudinal dimension of the toe portion of the shoe, the rotatable member 35 is rotated so as to move said toe cushion upwardly until same contacts with 75 the face of the toe portion of the shoe, and because slight movement of the support 42 about the pin 43 (Fig. 6) is allowed, on account of the play between the walls of the socket and the upper end of the screw 41, 80 said cushion may adjust itself so that it closely fits the toe portion of the shoe.

The entire arm 7, together with all of the machine parts associated therewith, is then adjusted vertically by axial rotation of the 85 rod 45, to bring the shoe in proper horizontal position with respect to the toe-molding plate 58, and the screw 21 is rotated to adjust the block 18 during this operation. Also, as the arm 23 is pivotally attached to 90 the support 22 and may move with respect thereto within the limits permitted by the slot and pin connection, the last and the shoe parts thereon may be adjusted to bring them into proper position. The hand-wheel 95 16 is then adjusted to move the member 12 longitudinally of the member 7 to bring the last to its proper position with respect to distance from the toe-molding plate. It is plain, of course, that all of these adjustments 100 need be made only when a run of shoes of different sizes are to be operated upon.

When the shoe has been properly positioned as described, the foot pedal 76 will be engaged by the operator and the forward 105 end thereof depressed. This will result in the carrier 51, which supports the toe-molding plate 58, being moved forwardly, and said toe-molding plate engages the last L in such a manner that the top face of said 110 plate is approximately alined horizontally with the top face of the last as it is positioned on the machine, and with the toe portion of the last extended into the cut-out portion of the plate 58, whereby the side 115 portions of said plate will engage the side portions of the last. This will result in the box toe material and the lining, if lining be used, being drawn closely about the toe portion of the last, so that the shoe is 120 provided with a smooth toe portion or tip. The toe-molding plate moves into contact with the shoe parts on the last just as the toggle 71 passes over dead center, hence said toe-molding plate will remain locked in its 125 advanced position until the toggle is broken by operating the trip lever 80. The function of the coil springs 65 is to permit the carrier 51 and plate 58 to yield slightly, if this be necessary to prevent injuring the 130

shoe. However, these springs are of sufficient strength to cause the box toe material and the lining to be drawn closely about the toe portion of the last.

5 After the toe of the shoe has been molded as described, and while the toe-molding plate is in contact therewith, the outer end of the foot pedal 86 is depressed to draw the heating and pressing iron 103 downwardly 10 into contact with the upper face of the last, and as said heating and pressing iron reaches the top of the last, the handle 101 is grasped and said heating and pressing iron is moved laterally in various directions in contact with 15 the top face of the last to press the lasting allowance of the shoe parts (which until this time was extended upwardly) horizontally and outwardly, to provide the shoe with an outwardly extended flange portion 20 at the toe portion thereof, said flange being pressed against the toe-molding plate 58. When the heated iron 103 is applied to the box toe material, said material will be softened, and the tar-like substance with 25 which it is treated will become sticky, or tacky, enough to cause the box toe material and the other shoe parts to stick together. Also, because of the soft condition of the material, it may be readily shaped to 30 produce the outwardly extended flanges as described.

After the outwardly turned flanges have been shaped as described, the heating and shaping iron 103 is permitted to move upwardly, and the weight 68 is moved to the 35 position in which it is shown in dotted lines in Fig. 3, in which position said weight will rest upon the outwardly turned flange of the shoe. The machine parts are allowed to remain in these positions until the flange on 40 the shoe has cooled and thus has taken on a permanent set, when the weight will be returned to its normal position and the carrier 45 51 and toe-molding plate 58 will be returned to their rearward positions by breaking the toggle with the aid of the trip lever 80, whereupon the last and shoe are ready for removal from the machine.

As already explained, the machine is a 50 multiple one, being made up of a plurality of duplicate sections, and therefore the operator may work on the shoe being operated upon by one section, while a shoe which he has previously worked on is drying on another section of the machine. Also, to simplify the construction of the machine, I employ but one heating and shaping iron 103 55 for use with a pair of sections of the machine.

60 While I have described my improved machine as being intended for use in forming outwardly turned flanges on shoes, it is obvious that it may be employed to form inwardly turned flanges on said shoes, in which 65 event the flanges will be pressed against the

last bottoms instead of against the toe-forming plates.

This application is a continuation in part of an application filed by me on or about June 26, 1926, bearing Serial No. 118,736. 70

I claim:

1. In a machine of the class described, an adjustable last support adapted to receive a last on which a shoe upper is arranged, a carrier movable toward and from the last, a toe-molding plate removably supported by said carrier and having an edge adapted to make line contact with the toe portion of the shoe upper on the last at the front and side marginal edges thereof and adjacent to the last bottom to draw the material forming said toe portion closely about the last, a support for said carrier mounted for movement, means for moving said support, and yieldable means for transmitting movement 85 from said support to said carrier.

2. In a machine of the class described, an adjustable last support adapted to receive a last on which a shoe upper is arranged, a carrier movable toward and from the last, a toe-molding plate removably supported by 90 said carrier and having an edge adapted to make line contact with the toe portion of the shoe upper on the last at the front and side marginal edges thereof and adjacent to the last bottom to draw the material forming said toe portion closely about the last, a support for said carrier mounted for movement, means for moving said support, yieldable means for transmitting movement from 95 said support to said carrier in one direction, and rigid means for transmitting movement from said support to said carrier in another direction.

3. In a machine of the class described, an 100 adjustable last support adapted to receive a last on which a shoe upper is arranged, a carrier movable toward and from the last, a toe-molding plate supported by said carrier and having an edge adapted to make 105 line contact with the toe portion of the shoe upper on the last at the front and side marginal edges thereof and adjacent to the last bottom to draw the material forming said toe portion closely about the last, means comprising a toggle for moving said carrier, said 110 toggle being adapted to be moved past center to maintain the toe-molding plate in contact with the shoe upper, and a trip lever for breaking the toggle when same is past center 115 so that said toe-molding plate may be removed from contact with the shoe upper.

4. In a machine of the class described, an 120 adjustable last support adapted to receive a last on which a shoe upper is arranged, a toe-molding plate, movable toward the last 125 and adapted to make line contact with the toe portion of the shoe upper on the last at the front and side marginal faces thereof and adjacent to the last bottom to draw the 130

material forming said toe portion closely about the last, horizontally adjustable means for supporting the toe portion of the last, said means including a horizontally guided 5 member, a vertically movable member carried by said horizontally guided member, a projection on said vertically movable member, and a toothed bar, the teeth of which are adapted to engage said projection, 10 whereby said horizontally guided member may be maintained in a fixed position, and means for moving the toe-molding plate.

5. In a machine of the class described, a vertically adjustable member, a horizontally adjustable member mounted on said vertically adjustable member, screw-threaded means for adjusting said horizontally adjustable member with respect to said vertically adjustable member, an adjustable last 15 support mounted on said horizontally adjustable member and adapted to receive a last on which a shoe upper is arranged, a toe-molding plate movable toward the last and adapted to make line contact with the 20 toe portion of the shoe upper on the last at the front and side marginal faces thereof and adjacent to the last bottom to draw the material forming said toe portion closely about the last, and means for moving the 25 toe-molding plate.

6. In a machine of the class described, an adjustable last support adapted to receive a last on which a shoe upper is arranged, a toe-molding plate movable toward the last 30 and adapted to make line contact with the toe portion of the shoe upper on the last at the front and side marginal faces thereof and adjacent to the last bottom to draw the material forming said toe portion closely 35 about the last, means for moving the toe-molding plate, heated means for wiping the lasting allowance of the shoe upper to provide flanges approximately parallel with the last bottom, and a weight arranged for movement to a position where it rests on the flange on the shoe upper to maintain said flange in the position to which it has been moved.

7. In a machine of the class described, a 40 last support adapted to receive a last on which a shoe upper including box toe material is arranged, an element positioned adjacent to the bottom of the last at the toe portion thereof, and heated means for wiping the lasting allowance of the shoe upper and of the box toe material outwardly in contact with said element to provide a flange approximately parallel with the last bottom.

8. In a machine of the class described, a 45 last support adapted to receive a last on which a shoe upper including box toe material is arranged, a plate positioned adjacent to the bottom of the last at the toe portion thereof, and heated means for wiping the lasting allowance of the shoe upper and of

the box toe material outwardly in contact with said plate to provide a flange approximately parallel with the last bottom, said heated means during formation of said flange being located out of direct contact with the 70 outer layer of material of the shoe upper.

9. In a machine of the class described, a last support adapted to receive a last on which a shoe upper including box toe material is arranged, a plate positioned adjacent 75 to the bottom of the last at the toe portion thereof, and heated means for wiping the lasting allowance of the shoe upper and of the box toe material outwardly in contact with said plate to provide a flange approximately 80 parallel with the last bottom, the heated means being so positioned with respect to the last and the elements comprising the shoe upper thereon that the box toe material is interposed between the outer layer 85 of material of the shoe upper and said heated means so the heat of said heated means will have free access to said box toe material.

10. In a machine of the class described, a last support adapted to receive a last on 90 which a shoe upper including box toe material is arranged, a plate positioned adjacent to the bottom of the last at the toe portion thereof, and heated means for wiping the lasting allowance of the shoe upper and of 95 the box toe material outwardly in contact with said plate to provide a flange approximately parallel with the last bottom, said heated means being movable during the flange forming operation in a plurality of 100 directions including transversely with respect to the major axis of the last.

11. In a machine of the class described, a last support adapted to receive a last on which a shoe upper including box toe material is arranged, a plate positioned adjacent 105 to the bottom of the last at the toe portion thereof, and universally movable heated means for wiping the lasting allowance of the shoe and of the box toe material outwardly in contact with said plate to provide a flange approximately parallel with the last bottom.

12. In a machine of the class described, a last support adapted to receive a last on 115 which a shoe upper including box toe material is arranged, a plate movable toward the last and arranged to make line contact with the toe portion of the upper on the last at the front and side marginal faces thereof 120 and adjacent to the last bottom, and heated means for wiping the lasting allowance of the shoe upper and of the box toe material outwardly in contact with said plate to provide a flange approximately parallel with 125 the last bottom.

13. In a device of the character described, forming means, a movable support for said forming means, means for receiving a shoe upper mounted upon a last and arranged to 130

present the toe of said upper to said forming means, a support for said last, the support for the forming means being movable parallel with the long axis of said shoe upper, means for causing said forming means to contact with the toe of said shoe upper, and an ironing pad adapted to contact with said last and the edges of said shoe upper to flatten outwardly the edges of said shoe upper.

14. In a device of the character described, forming means, a movable support for said forming means, means for receiving a shoe upper mounted upon a last and arranged

to present the toe of said upper to said forming means, the support for said forming means being movable parallel with the long axis of the shoe upper, a support for said shoe upper, means for causing said forming means to contact with the toe of said shoe upper, an ironing pad adapted to contact with said last and the edges of said shoe upper for flattening outwardly said edges, and a foot pedal for controlling the vertical movement of said ironing pad.

In testimony that I claim the foregoing I hereunto affix my signature.

WILLIAM KAUT.
